UNITED STATES PATENT OFFICE.

FRANK. M. HUNT, OF ROUND OAK, GEORGIA.

FOLDING UMBRELLA.

SPECIFICATION forming part of Letters Patent No. 508,717, dated November 14, 1893.

Application filed April 24, 1893. Serial No. 471,609. (No model.)

To all whom it may concern:

Be it known that I, FRANK. M. HUNT, a citizen of the United States, residing at Round Oak, in the county of Jones and State of Georgia, have invented certain new and useful Improvements in Folding Umbrellas, of which the following is a specification, reference being had therein to the accompanying drawings, in which—

10 Figure 1 is a vertical sectional view of the umbrella opened, the cover being removed to better show the construction; Fig. 2 a similar view folded; Fig. 3 a similar view showing it partly open; and Fig. 4 a detail view 15 showing more clearly the connection between the stretchers and the ribs.

The object of this invention is to produce a compactly-folding umbrella which shall be very simple and durable in construction and 20 which shall also be inexpensive as more fully hereinafter appears.

In the drawings, *a* designates the staff, which is constructed in several detachable sections in order to be capable of separation. 25 The ribs are each constructed of two sections *b b'*, the former having their upper ends pivoted to the usual stationary ring near the upper end of the staff and the latter being pivotally secured, at a point near their upper 30 ends, to the lower ends of the upper sections. The preferred device for pivotally connecting the sections of each of the ribs is a small clip *b''*, riveted to the lower section and having ears which embrace and are pivoted to 35 the extreme end of the upper section. The lower rib sections are bent at the point where the clips are attached so that the upper surfaces of the sections will come substantially flush with each other and the overlapped portions fit close together when the umbrella is 40 open, as shown in Figs. 1 and 4. The upper ends of the lower sections are provided with inwardly projecting parts *b²*, which are slotted longitudinally for the reception of the 45 pivots carried by the bifurcated upper ends of the stretchers *c*, the lower ends of the stretchers being pivotally attached in the usual manner to an ordinary runner *d*. Near the 50 upper end of the staff is placed the usual spring catch *e* to hold the umbrella open and above this catch is a similar catch *e'* which is

reversed so as to act as a stop and prevent the runner prematurely sliding higher up the staff. Secured on the lower end of each of the upper rib-sections is a spring-clasp *f* which 55 embraces the adjacent portion of the lower rib-section and clamps the sections together and holds them in alignment when the umbrella is unfolded.

This umbrella is opened and closed the 60 same as an ordinary one and there is no danger of it prematurely folding. When it is desired to fold it compactly, for packing in a valise, trunk, &c., it is simply necessary to press in the upper catch *e* and slide the runner up toward the upper end of the stick, which will throw the ribs and stretchers up to the position shown in dotted lines in Fig. 1. The upper ends of the outer rib-sections are then pressed inwardly toward each other, 70 whereupon these sections will become disengaged from the clamps *f* and all the parts will readily fold to the positions shown in Fig. 2, the outer or lower ends of the lower rib-sections pointing upward. Then by separating 75 the handle or staff sections the umbrella will occupy but a small space and will be in condition for packing away. In unfolding, the sections of the staff are first put together and the umbrella then inverted, the handle-end 80 pointing upward. The runner is then moved along the staff—past the spring-catches—to a suitable point near the handle, which action swings the outer ends of the rib-sections and stretchers out radially from the staff. Then 85 by holding the runner in that position until the umbrella is righted, so that its handle-end will point down, the outer rib-sections will easily swing outwardly to the position shown in Fig. 3; then by sliding the runner 90 up again on the staff the rib-sections will become locked together and be ready for use.

This umbrella will cost but slightly more than those of the ordinary construction and it may be continuously used without folding 95 as an ordinary unfoldable umbrella, if desired. Its main advantages lie in its simplicity, lightness, compactness and durability.

The slotted extensions *b²* on the inner ends of the outer rib-sections enable the parts to 100 be folded closer together, that is, they permit the sections of the ribs and the braces to

come closer together, when the umbrella is folded for packing, without straining the joints between the rib sections or bending said sections. In practice, a joint of this 5 character, or an equivalent loose joint, is found indispensable to avoid bending the ribs, &c.

Having thus fully described my invention, what I claim is—

- 10 In a folding-umbrella, a sectional staff, ribs pivoted thereto and constructed of two pivotally-connected sections, the upper ends of the outer sections overlapping the outer ends

of the upper sections and being provided with inwardly-turned slotted projections b^2 , 15 means for holding the sections of the ribs in alignment, a runner carrying stretchers whose outer ends are connected to the slotted projections b^2 of the lower rib-sections, and spring catches on the staff, substantially as described. 20

In testimony whereof I affix my signature in presence of two witnesses.

FRANK. M. HUNT.
